Robert Robb

Attorney

UNITED STATES PATENT OFFICE

2,066,712

CASEMENT WINDOW WEATHERSTRIP
MEANS

Elmer D. Barringer, Cleveland, Ohio

Application July 15, 1935, Serial No. 31,498

4 Claims. (Cl. 20—69)

The present invention embodies improvements in the art of weatherstripping and includes primarily novel construction of weatherstrip devices designed for French windows which are of the in-swinging casement type.

One of the objections heretofore incident to the use of swinging casement windows has resided in the difficulty of adequately weatherstripping such windows, especially for the prevention of the entrance of water. This invention, by the construction of the appliances employed, facilitates the rendering of the window both air and water-tight, under practical conditions of use.

The present improvements comprise a special formation of rain-drip means for application to the outer lower portion of the casement window, and a special form of hook weatherstrip carried by the same portion of the window beneath the rain-drip member for cooperation with the inwardly extending lip or flange of a weatherstrip channel that is located on the sill below the lower edge of the window when it is closed.

One of the objects of the invention resides in the provision of means upon the hook weatherstrip member acting as a gauge to assist in properly locating the rain-drip member for its proper attachment to the window so as to ensure a desired and necessary amount of clearance between the rain-drip member and the so-called channel weatherstrip on the sill.

Another object of the invention is the cooperative formation of the rain-drip member and the hook weatherstrip previously referred to, such that an effective bracing action of the inner lower portion of the rain-drip is obtained by peculiar interengagement between said portion and an attachment flange by which the hook weatherstrip is secured in place on the window.

Still another object of the invention is to so form the hook weatherstrip as to provide an attachment flange of relatively large area having a corresponding area of engagement with the outer side of the window, so that any tendency of the hook weatherstrip to buckle when secured to the window by its proper fastenings is obviated. Furthermore, the said attachment flange of the hook weatherstrip, by reason of its angular disposition to the hook member thereof and by reason of the size of the flange, affords the advantage of holding the hook member properly squared against the portion of the window on which it fits and to which it is secured by the suitable fastenings employed.

With the above and other objects in view as

will more fully appear hereinafter, certain preferred adaptations of my invention are illustrated in the accompanying drawing, in which—

Figure 1 is a fragmentary sectional view of a window frame showing the lower portion of an in-swinging casement type of window mounted therein as when closed, and illustrating the weatherstrip means of the invention.

Figure 2 is a fragmentary view in perspective showing more clearly the manner of mounting the rain-drip member and the hook weatherstrip member coacting therewith in proper relation upon the lower portion or edge of the window or sash.

Figure 3 is a view somewhat similar to Figure 1 but illustrating a modified formation of the hook weatherstrip and mode of coaction of the rain-drip member therewith; this view also illustrates a different type of channel weatherstrip member such as may be useful to employ in conjunction with my weatherstrip improvements hereinafter to be set forth in detail.

Figure 4 is a sectional view of another modification.

Similar reference characters refer to similar parts throughout the drawing.

This application is a continuation in part of my previous application for patent, Serial No. 708,681, filed January 27, 1934.

I shall first refer to Figures 1 and 2 of the drawing, which illustrate one adaptation or modification of my invention, and which constitute construction divided out of the application for patent previously identified. In these figures the main sill of the window frame is indicated at 1, and a stool 2 is shown adjacent thereto as a part of the frame construction in which the casement window or sash 3 is mounted. The mounting means for the sash 3 is not material to the invention, the type of sash shown being known as an in-swinging casement window sash. In the angle between the main sill 1 and the stool 2 of the window frame there will be seen to be mounted what may be termed a weatherstrip channel 4, the base of which rests upon the sill 1 and is attached thereto by a fastening 5. The channel comprises the inner vertical flange 6 which is in line with the outer side of the structure 2 and having an inner face which is aligned with the inner face or surface of the sash 3 when the sash is closed. The channel 4 additionally comprises the outer flange 7 having the weepholes 8 near its lower portion for the passage outwardly of any water which may be trapped in the channel, 55

there being provided at the upper edge portion of said flange 7 an inwardly extending lip or flange 9 according to construction known in this art.

The flange 9 is provided for cooperation with weatherstrip means carried by the window sash 3 and forms a part of the present invention. This weatherstrip means includes the hook member 10 having the hook portion 11 of somewhat U-form disposed so that the opening or recess 10 of the U faces outwardly. The lower side of the hook member 11 is bent downwardly and refolded upon itself, as shown at 11a, to provide a reinforced edge portion, the upper side of which is in the plane of the upper face of the lower side of said hook 11 and has free sliding engagement with the lip or flange 9, as seen in Figure 1. In the formation of the refolded portion 11a of the hook member 10 it is notable that the lower member of the hook 11 is deflected or bent downwardly at 20 an angle. The bend that permits the edge portion to lie with its upper surface in the plane of the upper surface of the lower part of the hook provides a longitudinal reinforcing rib so to speak, and this formation adds substantially to the 25 rigidity of the hook flange. Moreover, since the metal of the hook 11 and member 10 is very thin, if the edge of the part 11a were free and not countersunk as provided by me, the tendency of said edge would be to grab or engage the metal 30 of the part 9, causing sticking and interfering with the ease of operation of the device. Again, where the refolded portion is not flush or counter-sunk as described, there is formed a dirt catching 35 groove inwards of the projecting edge and such groove tends to hold dirt and foreign matter to an extent that reduces the efficiency of the sealing action of the hook, as will be self-evident to those versed in this art. In my construction no lodgment of dirt or foreign matter will ensue in 40 the use of the weatherstrip because the upper surface of the lower member of the hook 11 is substantially continuous and the efficiency of my seal for weatherstrip purposes is maintained under all conditions of service.

45 Projecting upwardly from the hook member 10 is an attachment flange 12, and I purposely make this flange of relatively large area so as to provide a relatively large vertical member extending upwardly at substantially a right angle to the 50 hook 10. The area of this member 12 is such that it reduces the liability of buckling of the same when the fastening means consisting of the nails or screws 13 are applied to the window to attach the part 12 thereto. Likewise, the formation of 55 the parts 10 and 12 and their relative sizes provides a considerable area for the angular section therebetween, facilitating the squaring of the hook member in proper relation to the recessed portion 14 of the lower edge of the window in 60 which the hook proper is seated.

Above and at the outer side of the flange 12 of the hook member 10 is disposed the rain-drip member 15 which consists of an overhanging body, an attachment flange 16 secured by nails or other 65 fastenings 17 to the sash 3, and an underhung or bracing flange 18 which projects inwardly from the overhanging body of the rain-drip member 15. In general form this rain-drip member 15 is known in the art, but its relative mounting 70 and cooperation with the portion 12 of the hook member 10 is a novel feature of the invention. Describing this feature more fully, it is notable that the flange 12 is formed longitudinally thereof with a pressed-out rib or bead 19. This rib or 75 bead 19 is located especially with a view to co-

operation thereof with the underhung flange 18 of the rain-drip member 15. In other words the inner edge of the flange 18 of the member 15, according to Figures 1 and 2, is designed to contact with the bead or rib 19 just above the same, 5 and when so engaged, after the hook member 10 has been secured in position by its nails or fastenings 13, the rain-drip member 15 will be properly positioned so as to afford ample clearance 10 between its lowermost portion and the uppermost portion of the channel 4, which uppermost portion is, of course, the flange or lip 9.

It is contemplated that the installer of my weatherstrip means, as herein described, will always first position the rain-drip member 15 so 15 that it is mounted in relation to the bead or rib 19 as shown in Figures 1 and 2, and thereafter the fastenings 17 may be driven in place to attach the member 15 to the sash 3, and the proper clearance previously referred to as regards the 20 parts 9 and 15 will be established.

Now I have illustrated in Figure 3 of the drawing a modified adaptation of my invention wherein the parts that correspond with the parts shown in Figure 1 are similarly numbered. The primary differences in the construction of Figure 3 from that of Figure 1 reside in the formation of the channel member, which is something not material to the invention because different kinds of channel members may be availed of for the 30 purposes of the invention. However, in the Figure 3 construction, the bead or rib 19 is located a little higher on the flange 12 than is the arrangement of said bead as illustrated in Figures 1 and 2. This calls for a cooperative disposition of the 35 parts 15 and 12 such that the inner edge of the flange 18 will be installed in contact with the part 12 just below the shoulder which is provided by the bead or rib 19. Under these conditions it will be apparent from Figure 3 that 40 the member 19 in its coaction with the part 18 of the rain-drip member 15 has a sort of interlocking relation such that a bracing effect between these parts is obtained. In other words, any tendency, by accidental pressure, or the im- 45 pingement of a blow against the outer side of the member 15, to force said member inwardly or flatten it against the window sash 3, is prevented because the part 18 has the said interlocking engaging relation with respect to the part 19. 50

The attachment flange of the hook member may be formed with a plurality of ribs or beads 19. One of said ribs may be located below the bracing flange 18 while the other one may be located above the same to thereby prevent move- 55 ment of member 18 in vertical direction.

When a plurality of ribs or beads is employed the same may preferably be formed, as shown in Figure 4, wherein both beads are of a V-like configuration as clearly shown at 20. Adjacent ends 60 of the V-like beads form a V-like recess 21, which extends longitudinally over the entire length of the attachment flange of the hook member 11. In this manner the flange 18 of the rain-drip member 15 may be held against displacement in 65 an upward as well as in a downward direction.

The upper end 22 of the attachment flange 12 is slightly bent, as shown in Figure 4, for engaging the rain-drip member 15, and a better positioning and securing of members 12 and 15, 70 with respect to each other and the sash, may be thereby facilitated.

It will be apparent that in regard to the adaptations of the invention illustrated herein the proper locating of the rain-drip member in rela- 75

tion to the flange 12 of the hook member 10 may be obtained with equal facility in the process of installation of my weatherstrip construction upon a window of the casement type.

5. The weatherstrip construction hereinbefore described has been found very efficient in practice, as regards its weatherstrip functions, in effectively rendering the casement type of window water-tight and weather-proof, and quite advantageous from the viewpoint of enabling the quick and proper installation and effective attachment of parts thereof to the window under practical conditions of installing work.

Having thus described my invention, what I claim as new and desire to secure by Letters Patent of the United States, is—

1. In weatherstrip construction for swinging casement windows, in combination, a window sash, a hook weatherstrip member carried by said sash and provided with a guide or gauge part thereon, and a separate rain-drip member having a portion to cooperate with said guide or gauge part of the hook member to facilitate the proper positioning of the rain-drip member on the sash, and fastening means for connecting the rain-drip member and the hook member to the sash.

2. In weatherstrip construction for swinging casement windows, in combination, a hook member for the lower edge portion of the sash, comprising a vertical flange extending at an angle thereto so that a lower corner portion of the sash may be received in the angle between said vertical flange and the hook member, means for securing the hook member to the sash, the said hook member adapted to coact with a weatherstrip member below the sash and said flange being provided with a protuberant rib-like gauge or guide part extending longitudinally of the flange, a separate rain-drip member secured to the sash at the outer side of and above the flange of the hook member, said rain-drip member having a portion adapted to be aligned with the rib-like gauge or guide part aforesaid, whereby to facilitate the proper positioning of the rain-drip member relatively to the hook member to afford a proper clearance between the rain-drip member and the weatherstrip member with which the hook member operates.

3. In weatherstrip construction for swinging

casement windows, in combination, a sash, a hook member applied to a corner portion of the sash and having an offstanding flange for attachment thereof to the sash, fastening means connecting said flange to the sash to support the 5 hook member properly upon the sash, the said flange being provided with an outwardly extending rib longitudinally thereof and forming a gauge part, and a separate rain-drip member comprising a metal plate overhanging the flange 10 of the hook member at the outer side thereof and attached to the sash, said plate being bent inwardly at its lower end to provide an underhung flange having the edge thereof engaged with the gauge part of the flange of the hook member 15 so as to enable proper positioning of the rain-drip member in relation to the hook member and a weatherstrip part with which the hook member may cooperate.

4. In weatherstrip construction for swinging 20 casement windows, in combination, a sash, a hook member applied to a corner portion of the sash and having an offstanding flange for attachment thereof to the sash, fastening means connecting 25 said flange to the sash to support the hook member properly upon the sash, the said flange being provided with an outwardly extending rib longitudinally thereof and forming a gauge part, and a separate rain-drip member comprising a metal plate overhanging the flange of the hook member 30 at the outer side thereof and attached to the sash, said plate being bent inwardly at its lower end to provide an underhung flange having the edge thereof engaged with the gauge part 35 of the flange of the hook member so as to enable proper positioning of the rain-drip member in relation to the hook member and a weatherstrip part with which the hook member may cooperate, the underhung flange of the rain-drip member 40 inclining upwardly and being disposed in interlocking engagement with and below the gauge part of the attachment flange of the hook member, whereby such interlocking engagement with the underhung flange of the rain-drip member 45 affords a bracing action against pressure inwardly on the rain-drip member in the direction of the sash.

ELMER D. BARRINGER.
